UNITED STATES PATENT OFFICE.

HARRY R. GEER, OF JOHNSTOWN, PENNSYLVANIA, ASSIGNOR, BY MESNE ASSIGNMENTS, TO BUDD WHEEL COMPANY, OF PHILADELPHIA, PENNSYLVANIA, A CORPORATION OF PENNSYLVANIA.

METHOD AND APPARATUS FOR ROLLING DISKS.

Application filed September 18, 1920. Serial No. 411,083.

My invention relates to a method and apparatus for rolling suitable blanks into disks which may have a relatively thick central portion and a thinner outer portion, or a 5 tapered outer portion either with or without a comparatively thick periphery. These disks may be used for many purposes and in various constructions, but are particularly adapted for automobile and other vehicle 10 wheels, agricultural implements, etc.

The object of my invention is to provide a method and apparatus for disk rolling which will produce disks from suitable blanks, and said disks may have a parallel 15 or tapered reduced form from the central portion towards the periphery, which are adapted to the uses outlined. Rolled disks have proven their superiority over machined turned disks in both quality and cost, and 20 my method and machine are particularly adapted to shape the disks rapidly without unduly distorting the grain of the metal and thereby increasing the strength and decreasing the cost of the disks.

25 My method of producing disks consists of taking a blank of steel, iron or other metal, preferably a flat circular plate of the proper thickness and weight to produce the desired disk, and if desired the blank can be 30 heated in a suitable furnace, and when heated the blank is placed upon a metal platen, the center portion of the same clamped or secured thereto, and in order to center the blank it may be provided with a 35 central perforation, which fits over a corresponding projection or stud on the platen. The portion clamped may be of any reasonable diameter, or as small as possible to provide the necessary holding surface. The 40

platen may be either flat or plane, or may have a slight taper to correspond with the taper to be given the disk, or may have a 45 groove in or near the periphery or elsewhere to produce a thickened portion of the disk if desired. In fact the platen may be of any form to suit the shape of the disk to be made.

50 After heating, the blank is clamped in position on the platen, the platen rapidly rotated, and one or more rolls are projected with force against the blank and gradually moved over the surface of the same to roll or spin the blank into the desired shape.

In doing this I prefer to first project the roll or rolls against that portion of the 55 blank near the center, thence traversing the rolls over the blank at a suitable speed toward the circumference, thus causing the outer portion of the blank to curl up from the surface of the platen, thereby eliminating the cooling effect of the platen thereon.

If the heated blank should be in contact with the metal platen for any considerable time, the heat would be conducted away 65 from the blank so rapidly that it would be difficult or impossible to make the plastic flow of metal by means of the rolls. As the rolls traverse from or near the center toward the periphery, the steel blank or disk is rotated by the rotating platen and the outer portion of the blank curves away from the platen contacting only with the air, and air being a non-conductor, the outer portion remains hot as the rolling action progresses 70 from the center toward the circumference.

I may use either one roll or more, and I 75 may rotate the platen and the desired pressure of the rolls against the blank or disk may be supplied in any manner or to any degree, as will be readily understood.

In order to produce a disk with a thicker portion I may have a groove in the platen near the periphery (as shown in Fig. 9) or elsewhere, or may stop the movement of the 85 rolls a sufficient distance from the edge of the disk, thus leaving thereon the thickened portion of the blank, or may move the rolls upwardly or away from the blank a certain distance to cause the thickening of the disk 90 where desired while rolling the same.

My invention further comprises apparatus 95 which firmly clamps the central portion of a blank and holds it against a rotating platen, which may be shaped to conform with the desired cross section of the disk, while a pair of rolls, arranged on opposite sides of the axis of the platen, frictionally engage and press forcibly against the blank as the rolls are fed toward the periphery of the platen 100 and the disk. The rotation of the platen and the blank clamped thereto is thus transmitted to the rolls which, as they are fed outwardly, roll, thin, taper or otherwise shape the blank and increase the diameter thereof 105 to the required degree. The blanks may be

of any reasonable thickness and diameter and are preferably of circular shape, although they may be of other shapes if desired. The rolls are preferably shaped to 5 act one as a roughing roll and the other as a finishing roll and the axes of the rolls are arranged on opposite sides of the axis of the platen substantially in alignment. As the blanks which I operate upon are comparatively thin and heated and their central positions are ordinarily not to be tapered, these must be held firmly and clamped by 10 said central portion upon the platen in order to prevent the tearing or distortion of 15 their centers due to the pulling action of the rolls on the other portion.

Having thus given a general description of 20 my invention. I will now, in order to make the matter more clear, refer to the two annexed sheets of drawings.

Figure 1 is a top plan view of my improved disk rolling machine with parts broken away to show the gearing for reciprocating the rolls; Figure 2 is a side elevation of my disk rolling machine, the right hand portion thereof being shown in a vertical section taken substantially on the center line of the machine; Figure 3 is a detail view showing the roughing roll, in dotted lines, superimposed on the finishing roll, in solid lines, to illustrate the relative action of the rolls on the blank as they are caused to traverse the blank from its central portion outwardly; Figure 4 is an end elevation of 25 my disk rolling machine with the reversing clutch mechanism shown in section; Figure 5 is an elevation partly in section of the end opposite that shown in Figure 4; Figure 6 is a longitudinal sectional view showing in detail a part of the driving mechanism for reciprocating the rolls; and Figures 7, 8 30 and 9 show a blank, a taper disk and a taper disk with thicker edge, respectively.

Referring now to the characters of reference on the drawings: The frame 1 of my disk rolling machine is provided with guides 2 in which are slidably mounted the columns 3 on which the roll shaft head 35 is adjustably secured. The lever 8 is fulcrumed at an intermediate point on the shaft 7 which is carried in the bearings 6 on the frame 1. The inner end 9 of the lever 8 works in a notch 10 in the equalizer bar 11 and the outer end 12 works in the recess 13 of the piston 14, which reciprocates in the cylinders 15 and 16. The cylinders 15 and 16 are provided with fluid pressure connections 17 and 18 respectively.

Pins 21 pass through the eyes 20 of the 60 equalizer bar 11 and engage the intermediate ears 22 of the link 23, which is hinged on the shaft 95. The ends of the shaft 95 are mounted in transverse bars 94, which 65 connect the lower ends of the columns 3 together in pairs. The transverse bars 94 car-

ry shoes 96, upon which the lower ends of the links 23 work as the equalizer bar 11 is reciprocated. Rollers 25 are mounted on shafts 26, which are carried in the bearings in the intermediate ears 22 and the outer ears 24 of the links 23. The rollers 25 ride on the contact shoes 27, which are secured to the frame 1, as the shaft head 35 is raised or lowered.

The table 31 is journaled on the central cylindrical portion 4 of the frame 1 and is supported by the annular roller bearing 19 upon which it rotates. An annular bevel gear 30, secured to the table 31 by the bolts 32, meshes with the pinion 29, which is 20 mounted on the main drive shaft 28. The main drive shaft 28 is journaled in the bearings 5 in the frame 1. Secured to table 31, so as to rotate therewith, is the platen 33 which is shown with a concave upper face 34 adapted to conform with one shape of disk that I desire to roll.

I do not confine myself, however, to the particular form of platen shown, as it is manifestly evident that other forms may be 40 used as previously mentioned herein without deviating from the intent or purpose of this specification.

The roll shaft head 35 has the transverse central rib 38, which is provided with the 45 boss 37 below the central socket 36. The roll shaft, which comprises two portions 41 and 42 having substantially aligned axes, is journaled at the ends in the bearings 43 and at the middle in the bearing 40, which 50 is provided with the bearing cap 39. Each portion 41 and 42 of the roll shaft has a groove 44, in which is mounted a threaded shaft 46. The threaded shafts 46 fit into and engage the nuts 45, which are slidably 55 mounted in the grooves 44 and are provided with projections 47. The projections 47 slidably engage the annular grooves 48 between the bearing rings 49 and the bushings 50 and 51, which are mounted in the rolls 52 and 53. The roll 52 shows one form of my roughing roll and the roll 53 one form of my finishing roll, but these forms may be varied as desired.

The outer ends of the roll shafts are provided with bearings 54 in which the threaded shafts 46 are journaled. The bevel gears 55 which are mounted on the outer ends of the threaded shafts 46 mesh with the pinions 56 on the outer ends of the intermediate 60 shafts 57. The inner ends of the shafts 57 have mounted thereon bevel gears 58 which mesh with the bevel gears 59. The gears 59 are rotatably mounted on the drive shaft 60 and each is provided with a female clutch element 104 adapted to frictionally engage the male clutch elements 63 and 64, which are mounted on and rotate with the drive shaft 60. The upper male clutch element 63 is splined on the drive shaft 60 and provided 65

with an automatic disengaging device which operates when the rolls 52 and 53 reach the inner limit of travel. The drive shaft 60 is journaled in bearings 65 and 66 and has at its lower end the bevel gear 61 which meshes with the bevel gear 62 on the main drive shaft 28.

The automatic disengaging means comprises a sheave 67 resiliently secured to the male clutch member 63 and the rock shaft 73 journaled in the bearings 71 and 72. Secured to the outer end of the rock shaft 73 on each side of the bearing 71 are the crank arms 70 which engage the trunnions 69 of the clutch fork 68. The trip lever 75 extends through a slot 74 in the roll shaft head 35 and is secured to the inner end of the rock shaft 73 and as the roll 53 is advanced toward the center it contacts with the lower end of the trip lever 75, thus turning the rock shaft 73, which raises the male clutch member 63, thereby preventing further rotation of the threaded shafts 46.

In order that the rolls may be adjusted for different thicknesses of disks, the roll shaft head 35 is provided with a screw adjustment whereby it may be raised or lowered to the required amount on the columns 3. Worm wheels 76, which engage the upper threaded portions 77 of the columns 3, are rotatably mounted in the enlarged portions 78 of the roll shaft head 35. Worms 79 mounted on the shaft 80 engage the worm wheels 76 and the shaft 80 is journaled in the bearings 81 and provided on its outer end with the hand wheel 82.

The roll shaft head 35 is provided with an upper fluid cooled rotatable clamping head 83, the lower end of which has the socket 84 that fits over the projecting center 88 of the lower clamping head 87. Cooling fluid is supplied to the upper clamping head 83 through the pipe 85, and may be discharged through a suitable outlet pipe connected to a tank or wasted as preferred.

Mounted in the central opening 89 of the platen 33 is the lower fluid cooled rotatable clamping head 87, which is provided with the projecting center 88. The clamping head 87 is arranged to rotate with the platen 33 when in the depressed position and to remain at rest when in the raised position, even though the platen 33 is rotating. The parts co-operating with the clamping heads 87 are mounted within the interior of the central cylindrical portion 4 of the frame 1. The clamping head 87 is mounted upon the flanged barrel 90 and a volute spring 91 surrounds the barrel 90 and is retained between the flange of the barrel 90 and the bearing collar 92. Between the bearing collar 92 and the set collar 106 there is a plurality of friction disks 105 which act as a brake to prevent rotation of the clamping head 87 when in the raised position. When the

clamping head 87 is in the depressed position it engages a shoulder within the central opening 89 of the platen 33 and the barrel 90 is supported on the ball bearing 107 and the clamping head 87 rotates with the platen 33. Cooling fluid is supplied to the clamping head 87 through the pipe 93 and discharged therefrom by another pipe or duct not shown.

The counterweights 97 for the roll shaft head 35 are secured to the shafts 98 which are journaled in the roller bearing 99 on the guides 2 of the frame 1. The arms which carry the counterweights 97 are each provided with a hook-shaped inner end 100 and the side plates 101 rest therein and engage the sockets 102 in the roll shaft head 35. The curled periphery of the blank is 108.

As illustrated in Figure 7, 86 is the flat circular blank which rests upon the flat platen 109. As illustrated in Figure 8, the platen 33 is tapered or dished to produce the tapered disk 103.

As illustrated in Figure 9, the platen 110 is provided with a dish or taper in its central portion and with an annular groove in its outer portion connecting with the same in order to produce a tapered disk with an enlarged rim portion as illustrated.

Assuming the parts of my disk rolling machine to be in the position as shown on the drawings, the operation is as follows: A suitable blank 86, see Figure 2, preferably heated and having a central hole therein is placed on the lower clamping head 87, which is in the raised position shown, the blank being centered by the hole therein and the central stud on the clamp which stud projects within said hole. Power is supplied to the main drive shaft 28, thereby rotating the platen 33 and the drive shaft 60. The blank 86 will not rotate yet because of the braking action exerted by the friction disks 105, which are held in close contact by the compression in the volute spring 91 as heretofore explained.

Fluid pressure is now admitted to cylinder 15 through the fluid pressure connection 17, thus advancing the piston 14 and moving the outer end 12 of the lever 8 to the right, whereupon the inner end 9 of the lever 8 moves to the left, shifting the equalizer bar 11 in the same direction. The rollers 25 then ride on the contact shoes 27, thus drawing the columns 3, which support the roll shaft head 35, downwardly in the guides 2 against the action of the counterweights 97. Assuming the adjustment of the roll shaft head 35 to be correct for the thickness of the blank used, the rolls 52 and 53 and the upper clamping head 83 will contact with the blank 86. If the contact is not that desired the hand wheel 82 may be turned in the required direction, thus moving the roll shaft head 35 up or down on the

columns 3 to correspond with the thickness of the blank 86. Having the adjustment correctly made, however, the blank 86 will be firmly held between the upper and lower 5 clamping heads 83 and 87 and the latter will be depressed into the rotating position.

As the roll shaft head 35 is lowered the female clutch element 104 on the lower gear 59 will engage the male clutch element 64, 10 thus rotating the threaded shafts 46 and traversing the rolls 52 and 53 outwardly from the center of the blank 86. The rolls 52 and 53 being in frictional engagement with the rotating blank 86 will also rotate 15 as they are traversed, thus rolling the blank 86 into conformity with the concave face 34 of the platen 33 and expanding its diameter to form the finished disk 103, as shown in Figure 5. As this rolling is done the portion 20 of the blank outside of the rolls curls upwardly and out of contact with the platen as shown at 108 in Fig. 3, thus conserving the heat thereof.

Fluid under pressure is now admitted to 25 the cylinder 16 through the fluid pressure connection 18, thus advancing piston 14 and the outer end 12 of the lever 8 to the left, whereupon the inner end 9 of the lever 8 moves to the right, shifting the equalizer bar 30 11 in the same direction. The rollers 25 then ride off the contact shoes 27 and the counterweights 97 raise the roll shaft head 35 to its upper position. The lower male clutch element 64 is thus disengaged and the female 35 clutch element 104 on the upper gear 59 will engage the upper spring pressed male clutch element 63, whereupon the rolls 52 and 53 will be advanced towards each other by the rotation of the threaded shafts 46.

40 As the rolls 52 and 53 advance towards the rotation axis of the platen 33, the roll 53 contacts with the lower end of the trip lever 75, thus turning the rock shaft 73 and raising the male clutch element 63, 45 thereby preventing further rotation of the threaded shafts 46 and automatically stopping the rolls 52 and 53 at their inner limit of travel.

In the meantime the upper clamping head 50 83 traveling up with the roll shaft head 35 releases the disk 103 and the lower clamping head 87 is raised clear of the rotating position by the volute spring 91. The disk is then removed and the machine is ready 55 for the insertion of another blank and the operation continues as before.

In connection with the operation, the manner in which the roll shaft is mounted should be noted. By removing the outer 60 bearing cap 43, the central bearing cap 39, and the housing caps over the gears 55 and 56, the roll shaft may be readily removed and the rolls dressed or new rolls or other parts in connection therewith replaced if necessary.

In working with heated blanks which are comparatively thin and therefore subject to rapid cooling it is necessary that the rolling action be very fast, otherwise the blank will have to be reheated and rerolled one 70 or more times in order to produce the required shape of the disk, thereby greatly adding to the cost of the finished disk.

75 My disk rolling machine is particularly designed to accomplish the rolling operation with one heating of certain types of blanks and without undue distortion of the grain of the metal. For other blanks and thinner disks I may reheat and reroll if desired.

80 To accomplish the purpose desired I place the roll axes in alignment and on opposite sides of the rotation axis of the disk, so that the rolls will tend to knead the material toward the periphery of the blank, so as to increase the diameter thereof to the required degree, as is necessary when a 85 rolled disk of tapered or reduced form is desired.

85 Furthermore, by using rolls having relatively short faces in contact with the blank the action of the rolls is practically a pure rolling action without any slip to produce radially curved distortion of the metal and thereby weaken the disk. The rolls and 90 the blank travel at the same velocity and as the pressure is limited to such a short element of contact the metal will be worked from the center in radial directions, thus shaping the disk so as to develop the full 95 strength of the metal.

95 It is also evident that my machine will produce disks rapidly as the different elements are co-ordinated to act with minimum physical and mental effort on the part of 100 the operator. The platen and other moving parts do not have to be stopped to remove the rolled disks or to insert the blanks and the automatic stop for limiting the inner travel of the rolls prevents any damage to 105 the machine through carelessness or oversight in operation.

110 Although I have described and illustrated my invention in considerable detail, I do not wish to be limited to the exact and specific details thereof, as shown and described, but may use such modifications in, substitution for, or equivalents thereof, as are embraced within the scope of my invention, or 115 as pointed out in the claims.

120 Having thus described my invention, what I claim and desire to secure by Letters Patent is:—

1. The method of rolling a tapered disk 125 which consists of placing a blank on a clamping head slightly elevated above a rotating platen but not rotating with the platen, lowering roll and another clamping head into contact with the central portion of the blank, thereby clamping the blank onto the 130

rotating platen, and traversing the blank with the roll outwardly from the center, thereby expanding and shaping the blank as desired.

5. 2. The method of rolling a disk which consists of placing a heated blank on a clamping head slightly elevated above a rotating platen, but not rotating with the platen, bringing roll and another clamping head into contact with the central portion of the blank, thereby clamping the blank to the rotating platen, and traversing the blank with the rolls outwardly from the center thereby expanding and shaping the blank as desired.

10. 3. The method of rolling a disk which consists in placing a blank on a clamping head slightly elevated above a rotating platen, but not rotating with the platen, bringing a roll and another clamping head into contact with the central portion of the blank, thereby lowering the first-named clamping head and causing it to rotate with the rotating table and securing the blank 25 against rotation on the platen, and traversing the blank with the roll outwardly to work it.

15. 4. A disk rolling machine comprising a rotatable blank supporting platen, and an axially reciprocable roll having a relative movement of approach and separation, means for reciprocating said roll, means for causing said relative movement of approach and separation, and a pair of clamping 30 heads adapted to hold a blank on the platen while the roll traverses the blank.

20. 5. A disk rolling machine comprising a rotatable blank supporting platen and an axially reciprocable roll having a relative movement of approach and separation, means for reciprocating the roll, means for causing said relative movement of approach and separation, and a pair of clamping heads adapted to hold a blank on the platen 45 as the blank is traversed by the roll, one of said heads being normally raised slightly above the surface of the platen and non-rotatable with the platen, to receive the blank initially, and means whereby said 50 clamping head is caused to rotate and lowered to allow the blank to rest upon the surface of the platen when the opposed clamping head is brought into operative engagement with the blank.

55. 6. A disk rolling mill comprising a rotatable blank supporting platen and a co-operating roll having a relative movement of approach and separation, said roll being axially traversable to work the blank, and 60 a pair of clamping heads rotatable, when clamping the blank in position, with the platen and adapted to hold a blank on the platen while the blank is traversed by the rolls.

65. 7. A disk rolling machine comprising a

rotatable blank supporting platen and a co-operating roll having a relative movement of approach and separation, said roll being axially traversable to work the blank and a fluid cooled clamping head adapted to 70 hold a blank on said platen while the blank is traversed by the roll.

8. A disk rolling machine comprising a rotatable blank supporting platen and a co-operating roll having a relative movement of approach and separation, said roll being axially traversable across the blank, and a pair of fluid cooled rotatable clamping heads to hold a blank on the platen 75 while the blank is traversed by the roll to 80 work it.

9. A disk rolling machine comprising a rotatable blank supporting platen and a co-operating roll carrying head having relative movement of approach and separation, 85 a roll on said head axially traversable crosswise of the blank, a clamping head on the roll head, and another clamping head on the platen for clamping a blank to the platen upon relative approaching movement of the 90 roll head and platen to cause the roll to operatively engage the blank.

10. A disk rolling machine comprising a rotatable blank supporting platen and a co-operating roll carrying head having a relative movement of approach and separation, 95 a roll on said head axially traversable crosswise of the blank to roll the same, rotatable clamping heads for holding a blank on said platen while traversed by the roll, one of 100 said clamping heads being carried by the roll head and the other by the platen, and at least one of said heads being fluid cooled.

11. A disk rolling machine comprising a rotatable blank supporting platen and a co-operating roll carrying head having a relative movement of approach and separation, a roll on said head axially traversable crosswise of the blank to roll the same, a 105 clamping head for holding the blank on the platen, said clamping head being normally held slightly elevated above the platen surface, and against rotation by an automatic brake, and means whereby, when the blank is clamped in position, the brake is 110 released and the clamping head lowered to allow the blank to rest upon the surface of the platen while being acted on by the roll.

12. In a machine of the class described, 120 the combination of a support for the blank to be rolled and a co-operating roll bodily rotatable relative to one another and movable toward and away from one another for rolling and to permit removal of the rolled 125 blank, means for shifting the roll crosswise of the support to roll a blank thereon, and means controlled by separation of the support and the roll for returning the roll to initial position. 130

13. A machine of the class described comprising a rotating support for the blank, a roll cooperating with said support, means for relatively moving said roll toward the support to apply it to the blank under pressure, and for relatively moving the roll away from the support, means for moving the roll radially of the blank, and means for automatically returning said roll to the central portion of the blank when the roll reaches a predetermined position in its movement away from the support.

14. A machine of the character described comprising an axial support for a blank, rolling means for the blank, means to relatively traverse the rolling means radially outward and inward as respects the axis, means to relatively move the rolling means to approach it toward and to separate it from the support, and automatic actuating devices for said traversing and approach and separation means cyclically relating the movements of the traverse and the approach and separation means.

15. In a machine of the class described, the combination of a support for the blank to be rolled and a cooperating roll bodily rotatable relative to one another, approach and separation mechanism between the roll and the support to move them toward and from each other to permit insertion and removal of blanks, traversing and retraversing mechanism to shift the roll crosswise of the support to roll a blank thereon and return the roll to starting position, and interlocking means between said mechanisms whereby operation of one of them brings about operation of the other.

16. In a machine of the character described, the combination of a support for the blank to be rolled, and a cooperating roll bodily rotatable relative to one another, a power-driven approach and separating mechanism to move the roll and the support toward and from each other, a power-driven traversing mechanism for the roll to shift it crosswise of the support to roll a blank thereon, interlocking means between said mechanisms whereby operation of one of them brings about operation of the other to carry the operations of the machine through a cycle, manual means to institute the cycle and automatic means to terminate the same.

17. A machine of the class described, comprising a rotating support for a blank to be rolled, a cooperating roll, means for causing the relative traverse and retraverse of said support and roll radially of the blank to roll the same and to return the roll to its starting position, and means for automatically stopping said relative radial movement at a predetermined point.

18. A machine of the class described, comprising a rotating support for a blank to be rolled, a cooperating roll, means for causing

said support and roll to approach each other to bring the roll into contact with the blank, means for relatively moving said roll and said support to cause the roll to traverse the blank crosswise while in working engagement therewith, and means controlled by said approaching movement for bringing about the traversing movement.

19. A machine of the class described, comprising a rotating support for a blank to be rolled, a cooperating roll, means for causing said support and roll to approach each other to bring the roll into contact with the blank, means for relatively moving the roll and support to cause the roll to traverse the blank radially, means to cause the separation of the roll and support, and means for causing the retraverse of the roll to the starting point, and means interlocking the means for causing the approach and separation and the means for causing the traverse and retraverse.

20. An apparatus for rolling disks comprising means for supporting a circular blank, a cooperating roll engaging the blank, traversing mechanism for progressively shifting said roll radially outward from the axis of the blank to gradually spin the metal of the same outward and reduce its thickness, approach and separation mechanism for moving the supporting means and roll relatively toward and from each other to permit insertion and removal of blanks and to apply rolling pressure, and independent means for adjusting said supporting means and roll relatively to each other to vary the thickness of the disc.

21. A machine of the class described comprising a substantially horizontal support for a blank to be rolled and a roll carrying head relatively movable toward and from each other to permit the insertion and removal of blanks, columns interconnecting said support and roll head, means for effecting said relative movement of said blank support and roll carrying head, and means for effecting an independent adjustment of one of said relatively movable members along said columns to vary the thickness of the blanks.

22. A machine of the class described comprising a support for a blank and a roll head arranged in vertical relation and relatively movable toward and from each other to permit the insertion and removal of blanks, columns interconnecting said support and roll head, and means for effecting an independent adjustment of the distance between said support and roll head by movement of one of said members along said columns, said means comprising screw-threads on said columns, and nuts cooperating with said screw-threads.

23. A machine of the class described comprising a support for a blank and roll

head arranged in vertical relation and relatively movable toward and from each other to permit insertion and removal of blanks, columns interconnecting said support and 5 roll head, and means for effecting an independent adjustment of the distance between said support and roll head comprising adjustable connections between one of said relatively movable members (support and 10 roll head) and each of said columns, and a device for simultaneously adjusting all of said connections.

24. A machine of the class described comprising a support for a blank and a roll 5 head arranged in vertical relation and interconnected by a plurality of columns, and means for effecting relatively small adjustments in the distance between said roll head and support comprising screw threads on 10 said columns, nuts cooperating with said screw threads, and mechanism for simultaneously rotating said nuts.

25. A machine of the character described comprising a horizontal platen to support 5 the blank, an overhead roll support reciprocable toward and from said platen, and rolls carried by said support on opposite sides of the platen axis and traversable laterally of said axis over the face of the 10 platen.

26. A machine of the character described comprising a horizontally-disposed rotatable platen to support the blank to be operated upon, an overhead roll support movable toward and from the platen, traversing rolls carried by said head and traversable thereon radially over the face of the platen, and roll traversing mechanism carried by the roll support.

27. A machine of the class described comprising a frame, a rotatably mounted table adapted to support a blank to be rolled, and a roll carriage having a relative movement of approach and separation, and means for 5 causing the relative movement of approach and separation of said table and carriage comprising a toggle-like connection between said frame and one of said relatively movable members.

28. A machine of the class described comprising a frame, a rotatable support for a blank to be rolled and a roll carriage having a relative movement of approach and separation, a roll on said carriage and adapted to operate upon a blank on said support, and means for causing the relative movement of approach and separation of said support and carriage comprising a toggle-like connection between said frame and one of said relatively movable members locking said relatively movable members in their position of approach while the blank is being operated upon by the roll.

29. A machine of the character described comprising a rotating support for a blank

to be rolled and a roll carriage having a relative movement of approach and separation, a traversable roll on said carriage and adapted to operate upon a blank while being traversed radially thereof, and means 70 for effecting said relative movement of approach and separation, comprising a plurality of toggle like devices arranged symmetrically about the axis of the machine and means for operating said devices simultaneously. 75

30. A machine of the character described comprising a rotating support for a blank to be rolled and a roll carriage having a relative movement of approach and separation, a traversable roll on said carriage and adapted to operate upon a blank while being traversed radially thereof, and means 80 for effecting said relative movement of approach and separation comprising a plurality of parallel shafts carrying toggle links, and means connecting said shafts whereby they are constrained to operate in unison.

31. A machine of the character described comprising a rotatable platen and a roll carrying head having a relative movement toward and from each other and interconnected through slidable columns serving to 90 guide said relatively movable parts in their movements toward and from each other, means interconnecting the ends of the columns, and approach and separation mechanism between the interconnecting means and one of the relatively movable elements. 95

32. A machine of the class described comprising a frame, a rotating support for a blank to be rolled and a roll carriage having a relative movement of approach and separation, a roll on said carriage for cooperation with the blank, columns connecting said roll carriage and frame and flanking said rotating support and serving as guides for said relatively movable parts in their approach and separation movements, said columns extending from the base of the frame to the extreme top of the machine and being in tension during the rolling operation throughout substantially their entire lengths. 105

33. A machine of the class described comprising a rotatable support for a blank to be rolled, and a carriage vertically movable relative to said support, a traversable roll carried by the carriage and adapted to operate upon a blank on said support while traversing radially of the blank, means for relatively moving the blank support and roll carriage including a counterbalancing device connected with one of said movable members. 115

34. A machine of the class described comprising a rotating blank support, a pair of traversing rolls having opposed axes, independent roll shafts for rotatably supporting the rolls, said roll shafts having their ad- 120

jaacent ends supported by relatively thin supports to permit the rolls to closely approach the center of the blank.

35. A machine of the class described comprising a rotating blank support, and a roll adapted to traverse the blank radially a fixed roll shaft for rotatably supporting the roll, and means for moving said roll along the fixed roll shaft.

10 36. A machine of the class described comprising a traversing roll, a fixed roll shaft for rotatably supporting said roll, and means comprising a thrust screw and a nut cooperating with said screw for moving said roll along the fixed roll shaft.

15 37. A machine of the class described comprising a rotating blank support, a pair of traversing rolls adapted to be simultaneously moved radially of the blank to roll the same, one of said rolls being a roughing roll and the other a finishing roll.

20 38. A machine of the class described comprising a rotatable blank support a pair of traversing rolls adapted to be simultaneously moved radially of the blank to roll the same, one of said rolls being a roughing roll and having an arcuate working face and the other of said rolls being a finishing roll and having a narrow substantially cylindrical working face and curved leading in face.

25 39. A machine of the class described comprising a rotating blank support, a roll adapted to be traversed radially of a blank on said support to roll the same, and mechanism for rotating said support and for traversing said roll deriving its power from a common prime mover.

40 40. In a machine of the class described, a blank support having a shallow recess in its surface gradually decreasing in depth from adjacent the center thereof toward the periphery and having a peripheral portion of greater depth than the portion adjacent thereto, together with means for rolling a blank into said recess to give it a varying cross sectional contour corresponding to the varying depths of said recess.

45 41. In a machine of the class described, a blank support having a shallow recess in its surface gradually decreasing in depth from adjacent the center thereof toward the periphery and having a peripheral portion of substantially uniform depth greater than the depth of the portion adjacent thereto, together with means for rolling a blank into said recess to give it a varying cross sectional contour corresponding to the varying depths of said recess.

50 In witness whereof I hereunto affix my signature.

HARRY R. GEER.
